KNITTING MACHINE

Azure W. Broadwell and Adam M. Cox, Lynchburg, Va., assignors to Lynchburg Hosiery Mills, Inc., Lynchburg, Va., a corporation of Virginia

Application January 10, 1935, Serial No. 1,233

12 Claims.

(Cl. 66—49)

Our invention relates to improvements in circular knitting machines having independent needles, and more especially to hosiery knitting machines, though not necessarily so limited. 5 The main object of the invention is to improve the operation of the machines in knitting fabrics with reinforced areas. It is common practice in the art to move a splicing yarn finger into and out of operation at each rotation of the machine but it has proved almost impossible to delimit accurately the spliced area in this way, as it is necessary for this purpose that this yarn be entered and withdrawn always at the same needles throughout the spliced area. In some 10 cases the needles have been split at a distance from the main feed to receive a splicing yarn fed by a separate guide remote from said feed but by our invention it is possible to feed all 15 yarns at the same point, thus simplifying the needle cam structure and avoiding an additional reciprocation of the needles in each spliced course.

According to our invention the splicing yarn guide remains in operative position throughout the splicing operation. This has another advantage, in that with the previous methods of sectional splicing the plating was uncertain and irregular, which is particularly undesirable where 20 yarns of different color or character are being knitted in plating relation, e. g. in so-called "white-foot" stockings with an inner white yarn plated on an outer colored yarn, in which case also the outer yarn is often silk or rayon while the inner yarn is cotton. By the use of our invention it is possible to knit reinforced areas with three yarns plated on one another and with the intermediate reinforcing yarn sandwiched between the face yarn and the inside yarn and positively held in place, whereby a cheaper yarn 25 can be used for splicing, but an improved product is made. For example, we may use a cotton splicing yarn between an acetate inside yarn and a rayon face yarn of regenerated cellulose, the two latter yarns entirely covering the intermediate yarn, or we may of course use any other like arrangement.

Another advantage of our construction is that we can make a double sole or high splice and mock wrap work (see Taubel Patent 1,619,788) 30 or float stitch plating on the same machine and at the same time.

A further advantage of our mechanism is found in the fact that other dividing cams, e. g. radially movable cams or cams less firmly supported than 35 ours, break a great many needle butts whereas

our combined dividing and center cam eliminates this trouble.

A further object of the invention is to provide an improved yarn feeding means designed for use particularly with other parts of our improved machine and which has been found to be essential for the making of our improved type of three-ply sectional splicing, but which is not necessarily limited to such use. Such yarn feeding means, in machines of the type above referred to, usually comprises a plurality of yarn fingers mounted in a set on a common pivot and each finger is provided with a separate yarn which is guided to the needles either alone or in conjunction with yarns from another finger or fingers. 15 Conventionally these fingers have each a vertical passage or orifice in the end adjacent the needle row and the yarn is inserted downward through such passage. In some situations it is a matter of very considerable difficulty for the knitter to 20 thread up such close-feed fingers as those shown at 16 and 17 of Cox Patent 1,891,023, this being notably the case in such machines as the Scott & Williams HH spiral knitting machine, exemplified in Scott Patent 1,282,958 and in the Scott & 25 Williams RI machine, exemplified in Scott Patent 1,641,554, September 6, 1927. Such fingers are threaded by inserting a yarn downward through the vertical passage from top to 30 bottom, then thrusting a small hook needle into the orifice (18 of the Cox patent) to catch the 35 yarn and then pulling the yarn inward through said orifice. The difficulty in threading up such machines is occasioned mainly by the crowded condition of the various parts and especially by the dial, which is very close to the yarn fingers and which hinders the knitter from obtaining ready access to said fingers. With our construction the yarn can readily be inserted without any interference due to the presence of the 40 dial or other similarly-located parts.

Referring to the drawings, which are made a part of this application and in which similar reference characters indicate similar parts:

Fig. 1 is a partial vertical section of a machine embodying our improvements.

Fig. 2, a partial elevation of a special yarn finger shown in Fig. 1, but on an enlarged scale;

Fig. 3, a section on line 3—3 of Fig. 2,

Fig. 4, an end view of the set of yarn fingers in a preferred operating position for splicing, looking from the right in Fig. 1,

Fig. 5, an elevation of a yarn finger, partly in section;

55

Fig. 6, an elevation of the needle cams in the position assumed during a splicing operation,

Fig. 7, a similar view, during heel and toe knitting,

5 Fig. 8, a development of yarn-finger controlling cams on the cam drum,

Fig. 9, a rear elevation of our improved center cam and its stand,

10 Fig. 10, a view of the heel portion of a stocking,

Figs. 11, 12 and 13 illustrate various uses of our invention, and

Fig. 14 shows the different needles used by us.

15 In the drawings, reference character 10 indicates a needle cylinder which may be of any conventional or desirable type and which is formed with needle slots for holding the needles 11, which needles are reciprocated by needle cams on a cam ring 12. The sinkers 13, the 20 sinker ring 14 and other coacting parts may be such as are commonly used.

25 A yarn finger is indicated at 15, this yarn finger being pivoted at 16 and being acted on by a spring 17, anchored at 18, to bring it to the position shown in Fig. 1. A thrust bar 19 serves to move the yarn finger about its pivot to an idle position where its yarn is not taken by the needles, this bar being moved by conventional pattern mechanism. In the machine here particularly referred to there are five yarn fingers as indicated in Fig. 4, the finger 15 supplying a splicing yarn, the finger 15a, the yarn that is at the inside of the finished stocking and the finger 15d the face yarn which appears at the outside of 30 the finished stocking, while fingers 15b and 15c are idle. It will be noted that finger 15d is somewhat elevated so that it feeds its yarn to all the needles right under their hooks, while fingers 15 and 15a rest on the throat plate and fingers 15b and 15c 35 are also located at a higher level than finger 15 in certain cases, all as determined by the pattern mechanism which governs them.

40 It will be noted that the yarn fingers 15 and 15d are provided with extensions or noses 20 at their forward ends, the purpose of these extensions being to guide their yarns close to the needles and directly under the hooks of the same. The yarn of finger 15 is at a higher elevation than that of finger 15a, and by reason of the relative positions of the fingers the splicing yarn is sandwiched in between the other two yarns during a splicing operation, at which time only the short-butt needles take yarn from finger 15, as hereinafter more fully explained. Adjustable 45 pins 21 are provided, as shown in Fig. 1, to determine closely the feeding position of such fingers as those at 15 and 15a, and set screws 22 are provided for holding the pins in adjusted position. Such yarn fingers as those at 15 and 15d 50 are provided with vertical passages 23, as usual, so that yarns may be passed vertically downward through said fingers if desired, or may be pushed out through the extensions 20 when it is desired that they shall lie close to the needles. In order 55 to facilitate threading up of such yarn fingers we provide a lateral recess 24 in one side face of each of the flat fingers, the recesses preferably tapering back toward the rear of the needle and being preferably on a level with the orifice in extension 20. This renders it a simple matter 60 to thread up by passing a yarn downward through the orifice 23 and then pushing it through the passage in nose 20 with a blunt instrument, the finger to be threaded being preferably in raised 65 70 75 (idle) position.

It will be seen that the recess 24 furnishes a relatively large guiding opening for such a blunt instrument, while the side face of the finger furnishes a much larger area against which the end of the instrument may rest while it is being manipulated to cause it to enter the recess 24 5 than is the case with the small hole in nose 20. The entrance to this hole is rounded off as shown at 20' and this feature, in conjunction with the large size of the recess 24 makes it easy to 10 thread up the finger without danger of abrading or cutting the yarn, the size of recess 24 also enabling us to round off this part so as to make the path of travel easier, where heretofore the 15 yarn turned at a right angle.

The needle circle comprises a segment of long butt needles and a segment of short butt needles, as usual in hosiery machines, the long butt needles being idled during the knitting of heels and toes and the short butt needles being progressively idled and returned to action by the usual pickers. As it is our intention to splice on all the short butt needles we have provided an improved cam for this purpose, comprising a combined top center cam and dividing cam, such 20 cam being shown at 25. It is mounted for sliding movement, circumferentially of the machine, on the usual standard 26 which also carries the bottom center cam 27. The standard is slotted at 29 and the slot holds a pair of screws 28 secured 30 to the cam 25, the length of the slot being such that the screws have a limited horizontal movement whereby cam 25 may move from the position of Fig. 6 to that of Fig. 7. In the first position it is close to the left hand stitch cam 30, so 35 that all the needles can travel unusually far to the left before being retracted, thus providing ample room for the needles to take the yarn of finger 15d before they are retracted and insuring that the long butt needles will not take the splicing yarn in their downward movement, said yarn being fed to the short butt needles directly under their hooks, but not being taken by the long butt needles. An unusually wide space is thus provided between the first feed 15d and the point 40 where the center cam begins to retract the needles, whereby we are enabled to perform various operations after the first yarn is taken and before the needles begin to move downward under control of the center cam. At this time the butts 45 of long butt needles, which butts are shown in solid black at 31, will pass under the center cam, but the short butts 32 of the short butt needles can pass by the cam 25 without being retracted, due to the fact that the cam 25 is reduced in thickness at 33. The path of the hooks of the long butt needles is shown in Fig. 4 at 34, while that of the short butt needle hooks is shown at 35, in so far as said paths are separate.

During reciprocatory knitting the cam 25 is 50 moved back and forth between the stitch cams 30 and 36 by the needle butts of the short butt needles so as to afford ample space for their passage. When knitting with three yarns as described the body of the stocking is composed of 55 the two main or body yarns of fingers 15a and 15d plated one on the other, but our invention also has utility in knitting a single ply stocking with plated areas reinforced by a splicing yarn, wherein also the plating is improved and the reinforced 60 areas are sharply defined by straight and clean lateral margins as above explained.

A drum 37 of conventional character actuates the push bars 19, this drum being provided with cams 38 arranged in five rows (Fig. 8) in co- 65 70 75 75

operative relation with the respective push-bars. Certain of the cams will be low, wholly or in part, as at 38a, for the purpose of elevating fingers to special feeding levels, reference being had to 5 finger 15d in Fig. 4 and to other levels shown in Figs. 11 to 13.

While these cams and yarn fingers are arranged for the present purpose, in the way shown in Fig. 8, it will be obvious that other arrangements are 10 within the spirit of the invention; e. g. the splicing finger might be at the extreme left of the set in Fig. 4, (i. e., the first finger may be used for this purpose) other fingers respectively might provide the inside yarn or the outer facing yarn, 15 etc. What is essential to our purpose is that the splicing yarn finger is held in feeding position throughout the making of a spliced area, instead of being moved in and out at each rotation of the machine. When bringing the finger 15 into and 20 out of action, as at the beginning and at the end of a splicing operation, it must of course be moved into and out of action during the time when the long butt needles are passing it, since otherwise the nose would strike the needle hooks and cause 25 damage.

Fig. 11 illustrates the utility of our special dividing and center cam for making float-stitch ornamentation in a stocking having sectionally spliced areas with straight and clean sides, the mechanism being shown as arranged for making three-layer spliced areas, plated as above described, although we do not limit ourselves to such three-layer splicing. According to this figure the yarn-fingers are as in Fig. 4, as are also the cams 25a, 27a and 30a but cam 36a is radially movable and is shown as being in retracted position, the needles being raised by means of jacks, as in Grothey Patent No. 1,678,385, July 24, 1928 or by other suitable means. Certain of the long-butt needles 31a as 30 illustrated at A are allowed to remain in low position so that their hooks follow line 45 as they pass the first finger 15d and thus they do not take the normally outside yarn of finger 15d. This 35 yarn extends along the chord of an arc of the needle circle and thus floats back of the inside 40 yarn which is taken by said needles A and knitted into stitches that appear on the face of the fabric. If the stocking has an outer black plating yarn and an inner white plating yarn, white figures 45 will thus be formed on the outside of the stocking. This operation is made possible by the wide 50 space between the first finger 15d and the point where the center cam begins to retract needles, but is impossible with the center cam in the usual 55 position midway of the two stitch cams 30a and 36a.

Figure 12 illustrates the making of mock wrap work in a machine employing our special center cam and the splicing finger which remains in 60 position throughout the knitting of a spliced area as in the case of Figs. 4 and 11. In this figure the cams 25b, 27b, 30b and 36b are or may all be duplicates of those shown in Fig. 6 but there is added a cam 46 in advance of the center cam, 65 said cam 46 depressing all the needles after they have taken the yarn of finger 15d, except certain needles with extra short butts indicated at B (see Fig. 14), which needles are interspersed among the short-butt needles 32b (and which may also 70 in some cases be interspersed among the long butt needles of the series) according to the pattern desired. These needles B remain elevated until they reach the center cam 25b and thus are enabled to take yarn from fingers such as 15c and 15d, 75 while fingers are controlled by cams 38 of drum

37, as usual. The path of the hooks of short butt needles 32b is indicated at 47, that of the long butt needles corresponding to 47 until their butts strike cam 25b, after which they follow path 34b while the extra short butt needle hooks take path 48. 5 47. At any time when such a finger 15b or 15c is in the lowered position of finger 15c in Fig. 12 i. e., between the levels of 15a and 15d, its yarn will be taken by such needles B as pass it at this time and thus a yarn of special color or weight 10 may be put into the fabric so as to make spots or figures therein which resemble wrap work figures or spots, such possibility being due to the wide space between finger 15d and the center cam. After passing such mock wrap finger the needles 15 are divided by cam 25b, as above described, so that all needles take the inside yarn of finger 15a, while only the short butt needles 32b take the splicing yarn at points where spliced areas are to be made. 20

Preferably the finger 15 is all the way down as shown in Fig. 4 but this is not essential, it being important only that the nose 20 be so located that the splicing yarn will be taken by the short butt needles and missed by the long butt needles. The 25 size of cam 46 is somewhat exaggerated in Fig. 12 (see also Fig. 13) to enable the action on the needles to be shown more clearly and therefore finger 15 is somewhat elevated to maintain the necessary relation between nose 20 and the needle 30 paths, the yarn fingers being also shown as somewhat spread apart for similar reasons. 35

Fig. 13 indicates a set-up for making the stocking of Fig. 10. In this case the cams 25c, 27c, 30c and 36c may be like those of Fig. 11, but a 35 radially-movable cam 49 is added in advance of the center cam and a suitably long series of extra short butt needles C (Figs. 13 and 14) is located at the middle of the set of short butt needles 32c. During the knitting of conventional parts the cam 40 46 is retracted but when the "block" or narrow high splice 52 is reached the cam 46 is advanced and a finger such as 15c, which is supplied with a splicing yarn at this time, is brought down to a level below that of finger 15d but above that of finger 15a. All needles take yarn from finger 45 50 15d and then all but the extra short butt needles are retracted to miss the splicing yarn of finger 15c, the hooks of the extra short needles following path 50 and all other needles taking path 51 55 up to the point where they are divided by cam 25c, after which the short butt needles and the extra short butt needles take path 34c. The finger 15 is out of action at this time, and all needles take the inside plating yarn of finger 15a. When 60 block 52 is completed down to the desired level for the usual high splice the finger 15 is brought down and remains in action until the parts 53 and 54 are completed. If the finger 15c and the cam 49 remain in action there is formed an extra 65 heavy spliced area at 53, at the point where the wear due to the shoe counter is greatest, this area including the two splicing yarns of fingers 15 and 15c, and the needles being divided as before so that the short butt needles, including the extra 70 short butt needles B, all take the yarn of finger 15 while the long butt needles miss said yarn. 75

It is to be understood, in accordance with the common practice in the knitting art, that in some instances two or more yarns may be supplied by 70 a single yarn eye or guide, both acting as one yarn and sometimes being fine yarns that supplant a heavier yarn for the purpose, and the language of the claims is to be understood in that sense. Other variations of structure and in the use of 75

our invention, in addition to those herein suggested, will be obvious to those skilled in the art as falling within the true scope of our invention, and therefore we do not limit ourselves to what is shown in the drawings and described in the specification, but only as required by the state of the prior art.

Having thus fully described our said invention, what we claim as new and desire to secure by Letters Patent is:

1. In an independent needle knitting machine for knitting sectionally spliced fabrics, the combination of a set of contiguous long butt needles, a set of contiguous short butt needles, a yarn finger positioned to supply a plating yarn to all the needles at a high level, a yarn finger positioned to supply a splicing yarn at a lower level to the short butt needles only, a yarn finger positioned to supply a plating yarn at a still lower level to all the needles, pattern means for holding the second named finger in active position throughout the knitting of a sectionally spliced area, and a cam set including means for lowering the long butt needles to a level where they miss the yarns of the second named finger, whereby the splicing yarn is sandwiched between the yarns of the first and third named fingers.

2. In a hosiery knitting machine having means independent of the stitch cams for elevating needles individually, the combination of a pair of stitch cams normally elevating needles from idle level, one of said stitch cams being radially movable to an idle position to permit non-elevated needles to cross its face at idle level, a set of short butt needles, a set of long butt needles, a top center cam mounted to slide away from said radially movable cam under impact of the needles, said cam being reduced at its lower end to divide the long butt needles from the remaining needles, a yarn finger for feeding a plating yarn to all the needles except the non-elevated long butt needles, and another yarn finger for feeding a second plating yarn to all the needles, whereby float stitch patterns are made at the 45 positions determined by non-elevation of long butt needles.

3. In a knitting machine, a set of long butt needles, a set of short butt needles, extra short butt needles interspersed among the other needles, stitch cams, a top center cam mounted to slide laterally under the impact of the needles, said top center cam being reduced at its lower end to divide long butt needles from the other needles, a cam having a face in advance of said top center cam, said cam being positioned so that said face will divide the extra short butt needles from the remaining needles, two spaced yarn fingers positioned to supply plating yarns to all the needles, and fingers between them adapted to supply mock wrap yarns selectively to said extra short butt needles.

4. In a knitting machine, a set of long butt needles, a set of short butt needles, a set of extra short butt needles interposed midway of the set of short butt needles, stitch cams, a top center cam mounted to slide laterally under the impact of the needles, said center cam being reduced at its lower end to divide the long butt needles from the other needles, and a radially movable cam having a face in advance of the top center cam, said cam being adapted to be positioned so that said face will divide the extra short butt needles from the remaining needles.

5. In a knitting machine, a set of long butt needles, a set of short butt needles, extra short

butt needles interposed among the other needles, spaced apart yarn guides for feeding body yarns to all the needles in plating relation, a yarn guide arranged to feed a splicing yarn into position to be knitted between the plated body yarns, means for isolating said extra short butt needles, and means for feeding a different yarn to said needles when so isolated.

6. A device as in claim 5, the means for feeding said different yarn being located between said spaced apart yarn guides.

7. In a knitting machine, a set of long butt needles, a set of short butt needles, a set of extra short butt needles interposed midway of said set of short butt needles, spaced apart means for feeding yarns to all the needles in plating relation, sectional splicing means including means for feeding a splicing yarn and means for operating the needles to knit said splicing yarn between said plating yarns, means to isolate said set of extra short butt needles, and means for feeding another splicing yarn thereto so as to be knitted between said plating yarns.

8. In a circular independent needle knitting machine, a series of needles arranged in sets, a stitch cam, means for feeding three yarns in plating relation to said needles including means for feeding a facing yarn to the needles close to their hooks, means for then lowering the needles so as to leave a set in relatively elevated position, means for feeding a yarn to said elevated needles, close to their hooks, and means for then feeding a yarn at a low level to all the needles to form the other face of the cloth.

9. In a hosiery knitting machine for knitting fabrics with sectionally spliced areas, needles arranged in sets having butts of different length, stitch cams, a top center cam constructed and arranged to permit needles of one set to pass at a higher level than needles of another set, a mounting for said cam permitting it to slide laterally under impact of the needle butts, feeding means comprising a set of adjacent yarn fingers, and means for holding certain of said yarn fingers in fixed position throughout the knitting of a spliced area so as to supply a splicing yarn and two body yarns in plating relation to the needles that pass the top center cam at the higher level while supplying only the body yarns to the other needles, so as to cause a splicing yarn to be sandwiched in the spliced areas between the two other yarns plated thereon.

10. In a hosiery knitting machine for knitting fabrics with sectionally spliced areas, needles arranged in sets having butts of different length, stitch cams, a top center cam constructed and arranged to permit needles of one set to pass at a higher level than needles of another set, feeding means comprising a set of adjacent yarn fingers, and means for holding certain of said yarn fingers in fixed position throughout the knitting of a spliced area so as to supply inner and outer face yarns and a splicing yarn in plating relation to the needles that pass the top center cam at the higher level while supplying only the face yarns to other needles, the position of such yarns being such that in the spliced areas a splicing yarn is sandwiched between the two other yarns plated thereon.

11. In a hosiery knitting machine for knitting fabrics with sectionally spliced areas, needles arranged in sets having butts of different length, stitch cams, a top center cam constructed and arranged to permit needles of one set to pass at a higher level than needles of another set, and

yarn feeding means for supplying inner and outer yarns and a splicing yarn in plating relation to the said needles that pass the top center cam at the higher level and to supply only the face 5 yarns to other needles, the relation of said yarns being such that the splicing yarn is sandwiched between the two face yarns in the sectionally spliced areas.

12. In a circular independent needle knitting machine, needles arranged in sets having butts 10 of different length, a stitch cam, means for caus-

ing one set of needles to approach the stitch cam at a different level from other needles, and means to supply three yarns in plating relation to one set of needles while supplying only two yarns to the other needles, the relation between said yarns being such that a splicing yarn is sandwiched between two face yarns in vertically extending sections of the fabric, substantially as 5 set forth.
